Des. 179,506
Patented Jan. 8, 1957

179,506

CIGARETTE AND MATCH HOLDER

Robert W. Bannon, Youngstown, Ohio

Application May 1, 1956, Serial No. 41,298

Term of patent 14 years

(Cl. D48—28)

FIG. 1

FIG. 2

FIG. 3

The side of the device not illustrated is a substantial duplicate of the side shown in Figure 3.

I claim:

The ornamental design for a cigarette and match holder, as shown and described.
